UNITED STATES PATENT OFFICE.

EUGENE RENAUD AND EUGENE PASTRE, OF NEW YORK, N. Y.

DESIGN FOR PICTURE-FRAMES.

Specification forming part of Design No. **7,107**, dated January 13, 1874; application filed November 29, 1873.
[Term of Patent 3½ years.]

To all whom it may concern:

Be it known that we, EUGENE RENAUD and EUGENE PASTRE, of the city, county, and State of New York, have invented a Design for Picture-Frames, of which the following is a specification:

Our invention consists in the design for a floral wreath for picture-frames, and in the design formed by the wreath, and the inner and outer parts or moldings of the frame.

We prefer to form the background for the wreath of velvet cloth, and to paint or print the wreath thereon; but this forms no part of our invention.

What we claim is—

1. The design of the floral wreath for picture-frames, as described and shown.
2. The design for picture-frames formed by a floral wreath and the inner and outer moldings, substantially as described and shown.

EUGENE RENAUD.
EUGENE PASTRE.
